PRINTING PLATE THINNING AND
SHAVING MACHINE

William F. Huck, Richmond Hill, N. Y., assignor
to R. Hoe & Co., Inc., New York, N. Y., a cor-
poration of New York; Irving Trust Company,
permanent trustee

Application February 2, 1932, Serial No. 590,352

18 Claims. (Cl. 29—21)

This invention relates to thinning and finishing machines for operating upon curved stereotype or other printing plates having for its principal objects the provision of an improved device 5 of the kind indicated that will effect a substantial saving in time and labor while more efficiently shaving and trimming said plates than heretofore possible with conventional mechanism.

Another object is to provide a machine for thinning and machining curved stereotype printing plates, of novel design and construction with means for effecting a rough cutting and an attendant fine or finishing shaving of printing plates at substantially one operation.

Another object is the provision of a device for thinning curved stereotype printing plates, incorporating means independently rotatable for giving a preparatory rough cut or thinning to a printing plate and a finishing shaving in substantially one operation.

A still further object is to provide an improved machine for thinning curved stereotype or other printing plates having a novel combination of means for effecting at one operation a rough cut 25 and a finishing shaving to said printing plates.

It is also an object of the invention to provide a thinning and finishing machine for operating upon curved printing plates of generally improved construction, whereby the device will be simple, durable and inexpensive in construction, as well as convenient, practical, serviceable and efficient in its use.

In the drawings wherein similar characters of reference indicate corresponding parts in the several views of the preferred form of the invention—

Figure 1 is a front elevational view, partly in section, with parts broken away, of an embodiment of my invention;

Figure 2 is an enlarged transverse sectional view, taken on line 2—2 of Fig. 1, looking in the direction of the arrows;

Figure 3 is a transverse sectional view, taken on line 3—3 of Figure 1, looking in the direction 45 of the arrow;

Figure 4 is a top plan view of the device, with parts broken away, as viewed in the direction of the arrow 4 of Figure 1, and

Figure 5 is an enlarged fragmentary sectional view taken on line 5—5 of Figure 2, showing details of construction of the plate ejecting means employed.

In the drawings wherein similar characters of reference indicate corresponding parts in the preferred form of the invention, a machine em-

bodying my invention is illustrated which may comprise a frame 10 including a base or foundation 11 to which are bolted or otherwise secured supporting frame members or pedestals 12, 13; and a housing 14, for a belt 15 and pulleys 16, 17; by which power is transmitted from a motor 18 also fastened to the base 11.

On the pedestals 12, 13 or means fastened thereon, a plate thinning or shaving rotating assembly 19 is rotatably secured, the assembly 19 including a comparatively large rotatable cylinder 21 provided with a separately revolvable smaller cylinder or roller 22 eccentrically mounted thereon and hereinafter described more fully, which may be considered as substantially a milling cutter having adjustable cutting means or knives hereinafter described for obtaining a coarse or preliminary rough cut. The cylinder 21 is provided with an adjustable knife or blade 24 for effecting a fine or finishing thinning cut after the coarse cut made by the knives of the milling cutter whereby at one operation of the machine A, or a partial revolution of the large cylinder 21, a stereotype or printing plate B may be thinned and shaved.

The body portion of the cylinder 21, as best shown in Figure 2, is divided into a plurality of segments 25, 26, 27, joined to a central hub 28 which is provided with journals 29, 31 mounted on bearings 32, 33 supported on the pedestals 12, 13 or means secured thereto and arranged in housings or journal boxes 34, 35 fastened to the pedestals 12, 13. As best shown in Figure 2, between the segments 25, 26 a channel or passageway 25' is provided, while between the segments 26, 27 a similar channel 26' is provided. The channels 25' and 26' serve to convey metal chips and shavings from the space enclosed by the plates 127, 128 into the chute 129.

The right-hand side of hub 28, as viewed in Figure 1, and the journal 31 secured to or formed integrally therewith are of hollow or recessed construction to provide a pocket 36 in order to accommodate a shaft 37, provided with a worm 38, a thrust collar 39 and journals 41, 42 and having secured or keyed on one reduced end of the said shaft 37 adjacent the journal 41 a gear 40 meshing with a gear 50 fastened to a reduced end 46 on a neck journal 47 formed on an axle 48 secured to the right-hand side of the cutting roller or milling cutter 22, the journal 47 being supported on a bearing 49 mounted on the hub 28. The left-hand side of the same milling cutter 22, as seen in Figure 1 has an axle 51 formed with a journal 52 supported on a bearing 53 also mount-

ed on the hub 28 at the left hand side of the cylinder 21 and enclosed in a journal box 54 secured to the body portion of the cylinder 21. The bearing 49, neck journal 47 and the immediate associated parts at the right-hand side of the milling cutter 22 are enclosed in a journal box 55 which coacts with the hub 28 of the cylinder 21 in housing the gears 40 and 50.

The housing or casing 35 which houses the hollow journal 31, worm 38 and other coacting parts together with details hereinafter described, is composed of two sections 51, 58 joined in any suitable manner and fastened on the pedestal 13.

On a reduced portion 59 of the hollow journal 31, within the casing 35, a worm wheel 61 keyed thereto is secured by a lock collar or nut 62, the worm wheel being engaged by a worm 63 arranged within the casing 35 and secured to a shaft 64 having a slipping gear 65, the hub 65' of which latter is fastened at one end of said shaft 64. The slipping gear 65, which serves to prevent damage or overloading of the moving mechanism of the present device and the power supply therefor by its capacity to slip or ride over its own hub 65' in case the stereotype plate should offer an undue resistance due either to defects in the material thereof or through setting the knives 24 and 81 too far outwardly of the respective peripheries of the cylinder 21 and milling cutter 22—includes the following details: The hub 65' mentioned above on which an outer annular section 135 having gear teeth is revolvably mounted. On a threaded portion of the same hub 65' a ring 136 is threadedly secured, the ring 136 being formed with a plurality of pockets 137 in each of which a spring 138 is arranged. The springs 138 press against an annular insert or member 139 which is frictionally engaged against the other annular section 135 and seated in a shouldered portion 141 thereon. Holes 142 are formed in the ring 136, to provide means for tightening or loosening the said ring 136 when desired. The shaft 64 has journals 66, 67 supported in bearings 68, 69 secured to the frame 10. The gear 65 meshes with an intermediate gear 71 rotatably mounted in the housing 35 and coacting with a gear 80, secured on an end of a shaft 70 journalled in the same housing 35. The other end of the shaft 70 has fastened thereto a worm gear 72 meshing with the worm 38 mentioned above. The gears 65, 71 and 80 constitute a train of gears enclosed in a housing 73, which may be a part of the housing 35 or a separate housing suitably fastened thereto. In combination with gear 72 and the two worms 38 and 63, the above mentioned train of gears serve to transmit power from the motor 18 via the belt 15 and pulleys 16, 17 and shaft 37 of the large worm gear 61 directly fastened to the cylinder 21, while the same shaft 37 via coacting gears 40 and 50 is revolving at comparatively high speed the milling cutter 22.

The milling cutter or cylinder 22, as best shown in Figures 1 and 2, comprises a body portion 74, having the axles 51, 48 reduced to provide the journals 52, 47 alluded to above, the said body portion 74, being provided with radially-arranged recesses or pockets 79, in each of which is secured a cutting knife 81, clamping held against one of the inclined walls of the said pockets 79 by a wedge or block 82, and adapted to be received therein. The block 82 is adjustably held in the pocket 79 by an adjusting screw 83, the stem of which is threadedly secured in a hole 84 provided in the said block 82, and in a registering threaded pocket 85 formed in the body portion 74 of the milling

cutter 22, it being understood that when the adjusting screws 83 are turned, the wedges or blocks 82 can be slid into and out of pockets 79, to a variable degree, so that the knives can be positioned as desired with a view to arranging same for the desired depth of cut in the curved stereotype plate B, which, as best shown in Figure 2 is arranged against the arched inner surface of a top frame member or web 86 joining the pedestals 12 and 13, and in the space between the said arched top frame and the periphery of the cylinder 21. The knife 24 of the cylinder 21 is of the same type as the knives 81 of the milling cutter 22, and is received in a tapering recess 87 accommodating a block 88 adapted to clampingly confine the knife 24 against one of the sloping walls of the said recess 87 when a screw bolt 89 threadedly engaged with said block and the segment 25 of the cylinder 21 is turned to operatively position or adjust the knife 24 for the fine cut desired.

The stereotype plate B is supported in the position shown in Figure 2 by a shelf 90, suitably fastened to the frame member 86, and by a plate 91 secured to and forming a part of cam-operated member 92 normally maintained in the operative position shown by a spring 93, which presses upwardly the stem of an eye bolt 94 connected by a pin 95 to the member 92. The said spring 93 is arranged in a pocket or recess 96 formed in the upper frame member 86 and can be adjusted to the desired tension by a nut 97 and washer 98, it being observed that the lower end of the spring 93 is engaged against the floor of the pocket 96 and at an upper end against the washer 98. Formed integrally with or secured to the member 92 is an arm 99 provided with a roller 100 at one end which is adapted to be coactively engaged by a cam 101 secured to or formed integrally with the member 21, as best shown in Figure 1—the cam 101 thrusting down the said arm 99 and thereby lowering or swinging downwardly the member 92 to permit the stereotype plate B to be removed. This is accomplished by means of a manually-operable plate-ejector or member 102. The said plate-ejector 102, which comprises an elongated bar 103, having a handle 104, at one end and a flange or projection 105, at another, is slidably mounted in an elongated pocket 106 formed in the segment 26 of the member 21, and by a plate 108 which is fastened in any suitable manner, as by the screws 109, to the said segment 26. A lug 110 secured on the body portion of the bar 103 is engaged by a spring 111 seated in a recess 112 in segment 26 and adapted normally to maintain the member 103 in the position shown in Figure 5 to be manipulated in order to eject the plate B shown in section, which is accomplished by grasping the handle 104 and drawing the plate ejector 102 out of the pocket 106 against the resistance of the spring 111 until the flange 105 riding in a slot 113 formed in the plate 108 comes in contact with the marginal edge of the said slot at one end, the stereotype plate B meanwhile having been thrust out sufficiently to be grasped and deposited on a platform 114 connected by brackets 115, 116 which are adjustably secured to the frame member 12 by screws 143 riding in slots 115', 116', formed in said bracket 115, 116. As best shown in Figure 2 in dotted lines the frame member 12 is provided with depending portions 144, 145, which are engaged against the lower surface or edge of the brackets 115, 116, the said portions having vertically-positioned adjusting screws 146 extending there-

through into the top frame member 86, the last-mentioned screws 146 serving to raise and lower the said brackets and consequently the platform 114 to the desired height for conveniently receiving and inserting stereotype plates, into the device. It will be understood that under normal operating conditions the outer annular section 135 of the gear 65 will be frictionally engaged with the hub 65' so that the latter and consequently shaft 64 and worm 63 will revolve as the section 135 revolves.

5 Rotary movement therefore will be communicated to the cylinder 21 and the cutting elements thereon. Should, however, the cylinder 15 21 oppose too great a resistance to the torque communicated by gear 65, the section 135 will slip or idle on the hub 65'. The slipping gear 65, it will be seen, thus provides an assurance against undue breakage of parts or of strains 20 leading to the same result.

By further inspection of Figure 2, it will be seen that the segments 25, 27 are provided with small pockets 117 which accommodate coil springs 118, which are engaged against the bottoms 25 of small plunger pistons 119 slidably arranged in the said pockets 117 and having pins 121 seated on the top surfaces thereof. The pins 121 are fastened to triangular shaped plates 122 on which latter plate-engaging or pressure rollers 123 are revolvably mounted. The plates 122 are pivotally secured to brackets or members 124 anchored by bolts 125 threadedly secured in the segments 25, 27. The brackets 124 have projections or lugs 126 which serve as stops to limit 30 the movement of the plates 122 which carry the small presser rollers 123, after the milling cutter 22, has turned sufficiently or made a partial revolution to carry the said plates 122 and plate-engaging or presser rollers 123 out of the arch of 35 the upper frame member 86 after the thinning of the stereotype plate B at each revolution.

Guides or deflectors 127, 128 are secured to the segments 25, 27 of the cylinder 21 to deflect metal cut or shaved from the inner curved 45 surface of the plate B into one or both of the passageways 25', 26' and thence into a chute 129 communicating with the said passageways 25', 26' fastened to frame members 12, 13, the guide 128 being provided with a sealing strip 50 130 of suitable material to prevent fragments of metal from getting into various adjacent parts and crevices.

As best shown in Figures 1 and 4, a finger 131 fastened to the hub 28 is adapted to engage an 55 arm 132 secured to a switch 133, mounted on platform 114,—as the assembly 19 rotates, after the milling cutter 22 and knife 24 have accomplished their work in thinning and shaving the stereotype plate B. The actuation of the 60 switch 133 by the coacting arm 132 breaks the electric circuit to the electric motor 18, consequently stopping the rotation of the cylinder 21 at a point where the milling cutter 22, knife 24 and presser rollers 121 have been carried without 65 the arched portion of the frame 86,—thus permitting the easy withdrawal of the stereotype plate by the plate-ejector 102.

The function and general manner of operation of the device has been in large measure indicated from the foregoing details but will be more fully apparent from the following brief description:

70 The stereotype plate B to be thinned is placed on the platform 114, aligned with the annular space between the arched upper frame member

86 and the cylinder 21, and then pushed into the said space until arrested by the flange 105 of the plate ejector 102. The plate B will now be in the position best shown in Figure 2; i. e., one end resting on the shelf or plate 91, the other 5 end yieldingly engaged by the member 92, the upper convex surface of the said plate B being engaged against the concave arched roof or under surface of the upper frame member 86.

When the circuit to the motor 18 is closed, the 10 cylinder 21 by means of the reduction train of gears which includes the two worms 38 and 63, will slowly revolve, while the eccentrically mounted milling cutter roller 22 will rotate at comparatively high speed, the pressure rollers 15 121, while the thinning operation is going on, applying an additional pressure or support to maintain the plate B during the thinning process and also to smooth out inequalities therein. The shaving knife 24 on the cylinder 21 following the 20 rotating milling cutter provides a clean accurate surface by shaving off the tool marks left by the said milling cutter. The thinning and shaving may be graduated from a comparatively heavy slice to a fine shaving, the entire operation being 25 completed at one partial revolution of the rotating assembly 19. The knives 81 of the eccentrically mounted milling cutter which extend longitudinally the full length of the stereotype plate B may be adjusted to cut from the inner curved 30 surface of the plate B, variable amounts ranging from a comparatively deep slice to a thin shaving, but is primarily intended to make the preliminary rough cut, while the adjustable knife 24 on the large cylinder 21 is intended to give 35 the finishing or fine shaving. When the operation is completed, the plate B is unlocked automatically as the cam 101 engages the roller 100 on arm 99, thereby thrusting down the latter and consequently depressing the member 92. 40 Almost simultaneously with this automatic unlocking or release of the plate B by the descent of the member 92, the finger 131 on hub 28 of the cylinder 21 engages arm 132 of the switch 133, thereby opening the circuit of the motor 18 45 and bringing the machine to a stop. The finished stereotype plate is now removed by drawing the bar 103 until the flange 105 has protruded the plate B beyond the end of the upper frame 86 sufficiently to be conveniently grasped and placed 50 upon the platform 114 to be conveyed thence as desired.

What I claim is:

1. In a device of the kind described for thinning and finishing a curved printing plate at one 55 operation, a rotatable cylinder having cutting means and provided with an eccentrically-mounted revolvable cutter, said cutter having its axis parallel with the axis of the cylinder, means for securing said curved printing plate on said device in operative position for cutting, said means being automatically disengaged after said printing plate has been thinned and shaved, and said cylinder having ducts effective for conveying cut metal from the plate by gravity to a point 60 without said cylinder while rotating.

2. In a device of the kind described, the combination of a rotating member having means secured thereto for shaving the inner curved surface of stereotype plates, a second member rotatably and eccentrically mounted on and having its axis in parallelism with the axis of said first-mentioned member, said second member having means fastened thereto for thinning the inner curved surface of said curved stereotype plate, 65 70 75

- said means being adapted to finish the surface left by the second member, and other means for pressing the stereotype plate while being thinned and shaved, means for automatically stopping both of said members from rotating after the stereotype plate is thinned and shaved, and means for ejecting said plate when desired, said last-mentioned means being arranged in said first-mentioned member.
10. 3. In a device of the kind described, a support, a frame secured to said support and adapted to operatively receive a curved stereotype plate, manually-operable, spring-pressed means for operatively confining said stereotype plate within said frame, other means for shaving the inner surface of the stereotype plate, a rotatable body, said last-mentioned means including a member eccentrically mounted upon said rotatable body, having cutting elements, power-driven means for simultaneously actuating both the member and body at different angular velocities for the thinning and shaving of a curved stereotype plate, presser means secured directly on said other means, said pressure means engaging said stereotype plate while being thinned and shaved, a discharge passage arranged in the rotatable body, and deflecting means positioned on either side of said eccentrically mounted member, said deflecting means serving to deflect metal cut from the said plate into the said discharge passage.
15. 4. In a thinning and finishing machine for a curved stereotype plate having an axis common to all points of the curve, means for supporting the plate, a carrier rotatable on the axis of the curve, a thinning cutter rotatably supported on the carrier with its axis eccentric to and in parallelism with the axis of the carrier and arranged to remove metal from the inside surface of the plate, and a finishing cutter secured to the carrier and adapted to finish the surface left by the thinning cutter.
20. 5. In a thinning and finishing machine for a stereotype plate having a curved surface and an axis common to all points on the curved surface, means for supporting the plate, a thinning and finishing assembly rotatable on the said axis, a thinning cutter rotatably supported on the assembly and having its axis eccentric to and in parallelism with the axis of the assembly, adjustable cutting instrumentalities secured to the said cutter for variably thinning the inside surface of the plate by removing material therefrom, and a finishing cutter secured to the assembly and adapted to finish the surface left by the thinning cutter, said finishing cutter having means to graduate the degree of finish on said surface.
25. 6. In a device of the kind described for thinning and finishing a curved printing plate at one operation, a rotatable cylinder having cutting means and provided with an eccentrically mounted revolvable cutter, means for securing said curved printing plate on said device in operative position for cutting, said means being automatically disengaged after said printing plate has been thinned and shaved, and means in said rotatable cylinder for receiving and discharging metal cut from a printing plate while the said device is in operation.
30. 7. In a device for thinning and finishing a curved printing plate, the combination of a rotatable cylinder, plate thinning and finishing means fastened to said cylinder, a rotary cutter operatively mounted on the cylinder, a frame adapted to receive a curved printing plate, means including a resilient supporting instrumentality for

5. maintaining a curved printing plate in operative position on the support, and other means directly mounted on the rotatable cylinder for deflecting metal into and discharging same out of the said cylinder.

8. A combination as specified in claim 7 wherein said resilient supporting instrumentality is automatically disengaged from the printing plate after the same has been operated upon.

9. In a device of the kind described for thinning and finishing a curved plate in one operation, a rotatable cylinder having cutting means secured thereto, a rotary cutter eccentrically mounted upon the cylinder, metal deflecting means secured to the cylinder and arranged on either side of the rotary cutter, passageways in the said cylinder adapted to receive metal deflected by the said deflecting means, manually operable plate ejecting means normally maintained within the cylinder, and plate engaging and pressing down means secured to the cylinder and positioned on either side of the said metal deflecting means.

10. An arrangement as specified in claim 9 wherein means are provided for automatically disengaging the printing plate after the same has been operated upon.

11. An arrangement as specified in claim 6 wherein a chute is provided for receiving cut metal from said last mentioned means.

12. In a device for thinning and finishing a curved printing plate having an axis common to all points of the curve, the combination of means for supporting the plate, a rotary carrier, a milling cutter eccentrically mounted on said carrier and adapted to remove metal from the inside surface of the plate, a finishing cutter secured to the carrier and adapted to finish the surface left by the milling cutter, a power shaft concentric with the axis of the rotary carrier, gear means secured to said power shaft and operatively connected to said milling cutter, and other gear means operatively connecting the power shaft with the rotary carrier for rotating the same, all of said gear means being located at one end of the carrier.

13. In a thinning and finishing machine for a stereotype plate having a curved surface and an axis common to all points of the curved surface, a frame closed at one end and open at the other end for insertion and removal of the plate, a carrier rotatable on the axis of the curve, a thinning cutter eccentrically and rotatably supported on the carrier and arranged to remove metal from the inside surface of the plate, a finishing cutter secured to the carrier and adapted to finish the surface left by the thinning cutter, a power shaft concentric with the axis of the carrier, and gear means arranged at the closed end of the frame and operatively connected to the carrier and the thinning cutter for rotating the same.

14. In a thinning and finishing machine for a stereotype plate having a curved surface and an axis common to all points of the curved surface, a frame, means connected to said frame for supporting the plate, a carrier rotatable on the axis of the curve, a thinning cutter eccentrically and rotatably supported on the carrier and arranged to remove metal from the inside surface of the plate, a finishing cutter secured to the carrier and adapted to finish the surface left by the thinning cutter, a passageway arranged in said carrier for discharging metal cut from said plate by said thinning cutter, and a chute secured to

the frame for receiving the said cut metal from the passageway.

15. In a device of the kind described, the combination of a rotating member, means secured to said member for shaving curved stereotype plates, a second member rotatably and eccentrically mounted on said first mentioned member, said second member having means fastened thereto for thinning the stereotype plate, a power shaft concentric with the first mentioned rotating member and positioned substantially at one end thereof, gear means operatively connecting said shaft with both of said members, and a single housing wherein said gear means and said shaft 10 rotate.

16. In a device of the character described, a carrier member, a driving shaft coaxial with the carrier member, means secured to said member for shaving a curved stereotype plate, means for thinning the plate, said first mentioned means being adapted to finish the surface left by the second mentioned means, bearing supports on the member adapted to rotatably support the thinning means with its axis substantially in parallelism with the axis of the said member, and means for driving both said carrier member and said thinning means from the said driving shaft.

17. In a device of the character described, a carrier member, a driving shaft coaxial with the

carrier member, means secured to said member for shaving a curved stereotype plate, means for thinning the plate, said first mentioned means being adapted to finish the surface left by the second mentioned means, bearing supports on the member adapted to rotatably support the thinning means with its axis substantially in parallelism with the axis of the said member, and means for driving both said carrier member and said thinning means from the said driving shaft, and 10 plate hold-down means secured to said carrier, said plate hold-down means being effective to maintain a stereotype plate in position to be operated upon by both of said means.

18. In a device of the character described, 15 means for shaving the entire curved inner surface of a curved stereotype plate, and a second means mounted on and coacting with said first-mentioned means for operating on the said inner surface to thin said plate preparatory to being 20 shaved by the first-mentioned means, said first mentioned means engaging only such portions of the plate as have been previously acted upon by the second means, and metal deflecting means arranged on either side of the second means for 25 deflecting metal and preventing same from interfering with the normal and efficient operation of the device.

WILLIAM F. HUCK.
